UNITED STATES PATENT OFFICE.

WILLIAM H. FISHBURN, OF DENVER, COLORADO.

HOLDING DEVICE FOR WINDOW-SCREENS.

SPECIFICATION forming part of Letters Patent No. 759,842, dated May 10, 1904.

Application filed December 13, 1902. Serial No. 135,139. (No model.)

To all whom it may concern:

Be it known that I, WILLIAM H. FISHBURN, a citizen of the United States of America, residing in the city and county of Denver and

5 State of Colorado, have invented certain new and useful Improvements in Sash-Fasteners; and I do declare the following to be a full, clear, and exact description of the invention, such as will enable others skilled in the art to which it

10 appertains to make and use the same, reference being had to the accompanying drawings, and to the figures of reference marked thereon, which form a part of this specification.

15 My invention relates to catches or holding devices for window-screens, my object being to provide a device which will automatically lock or catch when the screen is swung to the closed position, which may be easily detached when it is desired to open the screen, and

20 which shall also hold the screen tightly in place and prevent rattling during windy weather.

25 The device consists of a piece of material, preferably spring metal, attached to the rail of the screen and having an inwardly-projecting part provided with a shoulder and an inclined extension beyond the shoulder adapted to engage an opening in a bracket attached to the window-frame and slip under the top thereof until the shoulder of the device presses far

30 enough inwardly to engage the bracket, the upper part of the device being curved to form a finger-hold, whereby the screen may be drawn to the closed or locked position by an inward pull from the inside.

35 The invention will now be described in detail, reference being made to the accompanying drawings, in which is illustrated an embodiment thereof.

In the drawings, Figure 1 is a vertical section of the window-frame, showing a screen in side elevation with my improvement applied, the screen being open. Fig. 2 is a similar view showing the screen closed and in section. Fig. 3 is a view of the lower part of

40 the screen in the closed position. Fig. 4 is a perspective view of the device shown in detail.

The same reference characters indicate the same parts in all the views.

Let the numeral 5 designate the screen, 45 which is hung on the window-frame at 6 and arranged to swing outwardly, as shown in Fig. 1. The construction for hanging the

screen is the same as shown in my previous application, Serial No. 120,048, filed August 18, 1902; but no invention is claimed thereon in this application. Hence this feature will not be described in detail, since the improvement to be claimed in this application is equally applicable to a screen hung or mounted on any suitable swinging attachment.

To the lower rail of the screen is attached a device 7 by means of screws or other suitable fastening device. This device 7 is provided with a lower inwardly-projecting part 7^a, having an upwardly-projecting offset or shoulder 7^b and a downwardly-inclined lip 7^c, projecting beyond the shoulder. The upper portion of this device is curved, as shown at 7^d, to form a finger-hold, as heretofore described.

To the frame 9, just inside of the screen when closed, is attached a bracket 10, having extremities 10^a, fitted to the frame, and an upwardly-projecting part 10^b, adapted to engage the shoulder 7^b of the device 7 to hold the screen in the closed position. The outer edge 75 of the part 10^b of the bracket is bent slightly upwardly to facilitate the entrance of the lip 7^c.

It is evident that my improved holding device may be attached to any construction of 80 swinging screen whether it is hinged at the end or side.

Having thus described my invention, what I claim is—

The combination of a bracket attached to 85 the window-frame, and a device attached to the screen on the inside and having a lower part extending inwardly and bent upwardly to form a shoulder adapted to engage the bracket when the screen or window is in the closed position, the said device having a lip projecting inwardly beyond the shoulder and downwardly inclined to facilitate the entrance of the device to the bracket as the screen or window is closed, the upper part of the device on the 90 screen or window being bent downwardly to form a finger-hold, substantially as described.

In testimony whereof I affix my signature in presence of two witnesses.

WILLIAM H. FISHBURN.
